(57) **CLAIM**

The ornamental design for a fuel screen, as shown and described.

DESCRIPTION

FIG. 1 is a top perspective view of a fuel screen showing my new design;

FIG. 2 is another top perspective view thereof;

FIG. 3 is a bottom perspective view thereof;

FIG. 4 is a left side view thereof, the right side view being identical;

FIG. 5 is a front view thereof, the rear view being identical; and,

FIG. 6 is a top view thereof, the bottom view being identical. The relatively thin shade lines represent contour, not surface ornamentation.
